UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

SIGNAL ATTACHMENT FOR FILM REELS.

1,407,083.

Specification of Letters Patent. Patented Feb. 21, 1922.

Application filed December 9, 1916, Serial No. 135,953. Renewed March 30, 1921. Serial No. 457,053.

To all whom it may concern:

Be it known that I, NICHOLAS POWER, a citizen of the United States, and a resident of the borough of Brooklyn, county of 5 Kings, city and State of New York, have invented new and useful Improvements in Signal Attachments for Film Reels, of which the following is a specification.

This invention relates to signal devices for 10 moving picture machines, and has for its object to provide a signal device for indicating the failure of the lower reel to take up the film as fed from the machine as sometimes occurs in the operation of the machine 15 through breakage of the film or an accident to the driving mechanism of the reel. In my Patent No. 1,208,647, granted December 12, 1916, I have illustrated a mechanism for this purpose which I have found satisfactory in 20 practice with machines of a certain type. The apparatus of my patent effects its signal upon the rotation of the reel at an increased speed which ordinarily takes place as explained in the patent when the film breaks 25 or the load is otherwise removed. In case, however, the accident should be such as not to produce an increased speed of the reel shaft, the signal mechanism of this patent would not operate.

30 The apparatus of my present application is designed to sound the signal upon any slackening of the normal tension of the film, regardless of the speed of operation of the reel shaft, so that a failure of the mechanism from any cause will effect a positive warning.

In the accompanying drawings I have illustrated a preferred embodiment of the device of simple construction designed not 40 to interfere with any of the working parts of the machine and adapted for attachment to machines now in use at small cost.

In said drawings,

Fig. 1 is an elevational view of the lower 45 magazine of a moving picture machine of a well known type, with my improved signal device attached;

Fig. 2 is a detail view largely in section at right angles to Fig. 1.

50 In the drawings, 1 indicates the lower reel shaft which is rotatably supported in the frame of the machine and projects into the magazine at the center thereof to receive the reel 2 upon which the film 3 is wound, as it 55 is received from the machine.

The shaft 1 is usually driven in machines

of this character through a friction drive in order that its speed of rotation may accommodate itself to the increasing diameter of the reel of film on the reel. In the drawings I have shown one type of friction drive which has been found satisfactory for the purpose. The friction drive comprises a fixed clutch disk 5 attached to the reel shaft and a complementary friction disk 6 mounted 60 for rotation on the reel shaft and yieldingly pressed against the fixed disk by a spiral spring 7 surrounding the shaft between the hub of disk 6 and the collar 8 of the shaft.

A portion of the periphery of the disk 6 is formed with sprocket teeth whereby the friction disk 6 is continuously driven by means of a chain 9 working on a sprocket 10 on one of the shafts of the projecting machine 11.

The film is fed into the magazine through a suitable guide or "magazine valve" in the upper wall of the magazine beneath the machine, and near one corner of the magazine. Between the magazine valve 80 and the reel, and toward the edge of the magazine there is provided a guide roller 12 over which the film is trained in its passage to the reel. The wall of the magazine adjacent the position of the roller is slotted 85 and the shaft of the roller projects through the slot and is supported by one end of the bell crank 13 loosely mounted on the supporting frame of the machine adjacent the reel shaft.

Attached to the other arm of the bell crank is a spring pawl 14 whose free end projects over a disk or ring 16 attached to the friction disk 6 which is driven from the projecting machine. The ring 16 is provided at intervals with ratchet teeth 17 with their abrupt faces on the side away from the direction of rotation, so that the teeth in passing under a pawl will leave the pawl and then let it snap abruptly off the point 100 of the tooth. When the film is taut between the magazine valve and the reel, the guide roller 12 will be held at the upper inner end of its slot, in which position the projecting pawl is clear of the periphery of the disk. When, however, the film becomes slack, either through breaking of the film or failure of the driving mechanism, the rock arm 13 will drop and the pawl-carrying arm 105 will be swung toward the reel shaft into position for the end of the pawl to be engaged by the teeth on the disk 16 which is con-

- tinuously driven from the driving chain 9. The passage of the teeth under the pawl will alternately raise the arm and allow it to drop abruptly, causing the axle of the guide 5 roller to vibrate back and forth in the slot in the magazine wall and produce a signal sufficiently loud to be readily heard by the operator near the machine. The signal will take place as soon as the film becomes sufficiently slack for the guide roller to move the 10 slight distance permitted by its slot, and the operator can therefore correct the trouble before any appreciable amount of film is accumulated.
- 15 As soon as the tension on the film is restored, the pawl will be lifted out of contact with the ratchet disk. The unbalanced weight of the arm 13 is slight and does not add appreciably to the tension on the film.
- 20 A light spring may be used if desired to press the free end of the arm toward the lower end of the slot and thus add to the force of the contact with the end of the slot when the arm is vibrated by the cam.
- 25 It will be observed that the apparatus is exceedingly simple and may be applied to existing machines by merely cutting a slot in the magazine wall to accommodate the spindle of the guide roller and providing a 30 suitable fulcrum for the arm 13 of the machine. Also, of course, attaching to the disk 6 the ratchet ring or disk 16.

The signal is positive under all conditions liable to affect the operation of the machine, 35 and gives a distinctive signal which re-occurs at frequent intervals until the damage is corrected.

Other modifications may also be made in the device without departing from the spirit 40 of my invention or the scope of the appended claims.

I claim:

1. In a mechanism of the class described, 45 the combination of a winding reel, a signal mechanism having a part driven from the driving mechanism of said winding reel, a guide for the film or web to be wound on said reel, said guide being supported so as to tend to move in one direction against the 50 tension of the film or web and connections between said guide and signal mechanism for causing the latter to be actuated by the said driven part when the tension of the film or web is so reduced as to permit said guide 55 to move.

2. In a motion picture projecting apparatus, a receiving magazine for the film reel mounted for rotation in said magazine, a driving mechanism for said reel without 60 said magazine; a signal device operated by said driving mechanism, and means for effecting the operation of said signal mechanism comprising a film-engaged part within said magazine and connections between 65 said part and said signal mechanism, where-

by variations in tension of the film within the magazine cause said signal mechanism to be actuated.

3. In a motion picture projecting machine, the combination of a receiving magazine for the film, a reel-supporting shaft in the magazine, means for rotating said shaft from without the magazine, a signal device operated by said driving means, and means for causing the actuation of said signal device comprising a guide roller mounted in said magazine for a limited movement and having its shaft projecting through an aperture in the wall of said magazine, said roller being normally held during the operation of the machine in its extreme position away from said reel, and connections between the shaft of said roller and said signal mechanism whereby movement of said roller toward said magazine causes the actuation of 80 said signal device.

4. In a motion picture projecting machine, the combination of a receiving magazine for the film, a reel-supporting shaft for the magazine, means for rotating said shaft from without the magazine, a signal device comprising a notched member continuously 90 rotated by said driving mechanism and a sounding member mounted for movement into and out of the path of movement of the 95 notches of said notched member, and means for causing the actuation of said signal device comprising a guide roller mounted in said magazine for a limited movement and having its shaft projecting through an 100 aperture in the wall of said magazine, said roller being held normally during the operation of the machine in its extreme position away from the said reel support, and connections between the shaft of said roller 105 and said signal mechanism whereby movement of said roller toward said reel support moves said sounding member toward said notched member.

5. In a mechanism of the kind described, 110 a receiving magazine for the film, a winding reel therein, a guide roller for the film within the magazine, said magazine having a slot in its wall through which the axis of said roller projects, a movable support for 115 said roller adapted to lie of its own weight in a position to entrain the roller away from the direct path of the film to the reel, a cam carried by the driving shaft of the reel and adapted to engage said movable support 120 when in its above described position and vibrate said roller in its slot, said slot being of a length such that the pull of the film under the normal winding tension will maintain said support out of contact with the 125 cam.

Signed at New York city, in the county of New York, and State of New York, this 6th day of December, 1916.

NICHOLAS POWER.
